UNITED STATES PATENT OFFICE.

CHARLES E. YOUNG, OF SHENANDOAH, IOWA.

GLOVE OR MITTEN.

1,426,029.

Specification of Letters Patent. Patented Aug. 15, 1922.

Application filed June 8, 1921. Serial No. 476,023.

To all whom it may concern:

Be it known that I, CHARLES E. YOUNG, a citizen of the United States, residing at Shenandoah, in the county of Page and State of Iowa, have invented certain new and useful Improvements in Gloves or Mittens, of which the following is a specification.

This invention relates to hand coverings, and has as an object the provision of a glove or mitten the thumb of which is reinforced at its connection with the body of the garment at the points where the greatest strain comes upon the seams.

15 An illustrative embodiment of the invention is shown in the accompanying drawings, in which—

Fig. 1 is a side view;

20 Fig. 2 is a view taken from the left of Fig. 1, with the garment flattened from the position shown in Fig. 1;

Fig. 3 is a detail section on line 3, 3 of Fig. 2;

25 Fig. 4 is a plan view of a blank for the hand portion of a mitten;

Fig. 5 is a plan view of a blank for the thumb portion of a two thumb mitten, showing how the same is cut from a strip of material; and

30 Fig. 6 is a view of a portion of the mitten of Fig. 2 with the end of the thumb removed and the fabric laid open to display the reinforcements.

For purposes of illustration, the two thumb mitten is chosen, being the type of mitten disclosed in a patent granted to J. I. Brorby, September 20, 1904, No. 770,670, wherein the hand portion of the mitten is indicated at 10 and the thumb at 11.

40 The blank from which the hand portion 10 is formed is shown at 12, Fig. 4, while the hole for the attachment of the thumb is shown at 13. When the mitten is sewn it is folded about line 14, thus producing a seam at the point and at the outside edge in the well known manner. To provide reinforcement for the seam of the mitten at the points where the greatest strain comes integral tabs 15, 16 and 17 are formed when 45 the thumb hole 13 is cut, the tabs projecting into the hole. When the thumb blank 18 is secured to the margins of the hole 13 the edges of the thumb blank, which are secured thereto, pass across the bases of the tabs 15, 50 16 and 17, the curve of the blank 18 being a regular curve at the portions where the

same cross the bases of the tabs. To provide a reinforcement at a fourth point upon the seam between the thumb and the body of the mitten a tab 19 is preferably formed 60 upon thumb blank 18. The seam securing the thumb blank and the mitten crosses the base of this tab in a manner already described for tabs 15, 16 and 17. When the seams are formed which attach the thumb 65 blank to the hand blank the seam is carried, as indicated in Fig. 6, in a regular curve about the opening 13 forming the seam at 20. In addition, supplementary seams 21, 22, 23 and 24 are carried about 70 the margins of the tabs 15, 16, 17 and 19, which tabs overlap the material of the adjacent blank.

The location of the tab 15 is such that it not only reinforces the seam connecting the 75 thumb to the mitten but also reinforces the seam securing together the two edges of the thumb blank. The points chosen for this and the other reinforcements are the points where the greatest strains upon the seam 80 come when the garment is in use. An additional tab of the size of 15, 16 or 17 could not be provided of the material of the hand blank as is shown by Fig. 4 and the tab 19 can be cut integral with the thumb blank 85 without waste. To prevent the edge of the tabs from catching on external objects all of the tabs are kept on the inside of the garment as indicated in Figs. 1 and 2. Obviously the invention could be applied to 90 gloves as well as to mittens.

The form of the blank 18 from which the two thumbs are produced is considered to be very advantageous, because of the effect of this form upon the number which may be 95 cut from a given amount of material. As shown in Fig. 5 the tab 19 of successive blanks is cut from the material which remains after cutting the cleft portion 25 of one blank from a strip of material 26. 100 Therefore only the amount of material which appears between the dotted line 27 in Fig. 5 and the full lines at the end of the blank 18 is waste material.

Minor changes may be made in the physical embodiment of the invention without departing from its spirit.

I claim:

1. A hand covering comprising, in combination, a hand portion having a thumb 110 opening, a plurality of tabs integral with said hand portion projecting into said open-

ing, a thumb portion having a tab thereon, said thumb portion secured to said opening by a seam, said tabs each crossing said seam at points where the greatest strain will come, and secured to the material upon the other side of the seam.

2. A hand covering comprising, in combination, a hand portion having a thumb opening, tabs integral with said hand portion projecting into said opening, a pair of thumbs made from a single piece of material secured to said opening by a seam, a tab integral with said thumb material, said

tabs crossing said seam at the points of greatest strain and secured to the material 15 of the opposite part.

3. A hand covering comprising in combination a pair of thumbs made from a single piece of material, a hand portion having a thumb opening, a tab integral with said hand portion projecting across the seam uniting the thumb and hand portion and across the seam closing said thumbs.

In testimony whereof I affix my signature hereto.

CHARLES E. YOUNG.
